his Attorney.

UNITED STATES PATENT OFFICE.

CLINTON E. SANKEY, OF ELLWOOD CITY, PENNSYLVANIA.

FOOT PROTECTOR.

Application filed May 18, 1927. Serial No. 192,360.

This invention relates to foot protectors and more particularly to a combined toe and foot protector adapted to be worn over the shoes of workmen in industrial plants to protect the feet of the workmen against falling objects.

In rolling mills and other industrial plants workmen are often engaged in handling heavy objects such as billets weighing more than a hundred pounds, and in many instances such objects are allowed to slip or fall either on the feet of the workman himself, or onto the feet of other workmen, causing crushed toes and other painful injuries.

The present foot protector is constructed of relatively light metal, but due to its novel construction has sufficient stiffness and strength to withstand the blows from any object that a man can handle. Also due to the novel shape and construction of the foot protector of this application, any blow or shock delivered to the foot protector will be delivered by the protector directly to the ground, due to the fact that the body of the protector bridges over the wearer's foot and has its lower edges in engagement with the ground.

In the drawings—

Figure 1 is plan view of the foot protector of this invention.

Figure 2 is a rear end view thereof.

Figure 3 is a longitudinal sectional view of the protector shown as applied to the foot of a wearer.

Referring more particularly to the drawings, the numeral 2 designates the body of the foot protector guard as a whole, which is generally arched or convex in cross-section to bridge over the forepart or toe and instep of the foot of the person wearing the same. The body 2 has an open bottom and is of a width sufficient to clear the sides of the shoe of the wearer and of a height sufficient to clear the top of the foot when the lower edges of the body are in engagement with the ground.

The body 2 of the protector is preferably made of a relatively light gage metal plate and is forged or pressed into shape from one piece of plate. A plurality of transversely extending and one centrally arranged longitudinally extending stiffening and reinforcing ribs 3 and 4, respectively, are pressed up

in the body and have a convex cross-section. The ribs 3 and 4 serve to materially strengthen the body 2 against collapse and permit a lighter gage metal to be used for the body than could otherwise be used.

The rear ends of the lower edges of the body 2 are cut away to form offsets 5 which terminate close to the underside of the arch of the shoe of the wearer, and a flexible tie member 6 is riveted or otherwise secured to the sides of the body 2 at the offsets 5 and extends transversely of the body. The tie member 6 extends under the arch of the wearer's shoe and serves to prevent the spreading of the side portions of the body, and also serves to hold the body of the protector down on the foot of the wearer.

A securing strap 7 has one end secured to one side of the body 2 and is adapted to be extended around the ankle of the wearer and have its other end detachably and adjustably secured by a buckle 8 secured by a short length of strap 9 to the other side of the body 2.

The function of the foot and toe guard described above will be apparent from the above description. Heavy objects dropped or allowed to fall on the feet of the wearer will be stopped or deflected without injury to the feet by the stiff metal body 2.

While I have shown and described one form of my invention, it will be understood that I do not wish to be limited thereto since various modifications may be made without departing from the scope of my invention as defined in the appended claim.

I claim:—

A toe and foot protector comprising a metal body portion generally convex in cross-section and shaped to fit over the toe and instep portion of a shoe encased foot of the wearer, said body portion being of greater width than the wearer's shoe so that its side edges will be free to engage the ground, said body portion being provided with a plurality of transverse stiffening and reinforcing ribs and at least one longitudinal stiffening and reinforcing rib, and means for securing said protector to the foot of the wearer.

In witness whereof, I have hereunto signed my name.

CLINTON E. SANKEY.
